UNITED STATES PATENT OFFICE.

JOHN C. RINGE, OF BRIDGEPORT, CONNECTICUT, ASSIGNOR TO THE SINGER MANUFACTURING COMPANY, A CORPORATION OF NEW JERSEY.

SEWING-MACHINE.

1,269,118.

Specification of Letters Patent. Patented June 11, 1918.

Application filed August 4, 1918. Serial No. 113,063.

To all whom it may concern:

- Be it known that I, JOHN C. RINGE, a citizen of the United States, residing at Bridgeport, in the county of Fairfield and State of Connecticut, have invented certain new and useful Improvements in Sewing-Machines, of which the following is a specification, reference being had therein to the accompanying drawings.
- 10 This invention relates to improvements in lock-stitch sewing machines for effecting, at a single operation, three parallel seams and has for its object to provide means capable of producing parallel seams of like or unequal lead.
- 15 In the earlier use of the present class of three-needle stitch-forming mechanisms the loop-takers are arranged in triangular relationship and their coöperating needles in like relationship, which arrangement of loopers and needles effect three parallel seams in which the inner seam is, of necessity, shorter at the finishing point than are the two outer seams and in the stitching of 20 certain products this is desirable while in certain other products it is desirable that the separate lines of seam formation be completed at the same point in the fabric, and to accomplish the object of the present invention there is herein provided means for effecting the coöperation of needles and the loop-seizing points of their respective loop-takers in a given line at substantially right angles to the lines of seam formation or at 25 an angle to said given line.
- 25 In the accompanying drawings illustrating the invention, in the several figures of which like parts are similarly designated, Figure 1 is a view in front side elevation of the right and left hand loop-takers and certain elements of the actuating mechanism of the latter carried by the sewing machine bed-plate, the feed-dog, its carrying bar and the right and left hand slide-plates 30 being shown in section. Fig. 2 is a plan view of the front end portion of the sewing machine bed-plate with the right and left hand slide-plates omitted to bring to view the loop-takers, the needle or throat-plate and the back slide-plate being shown in dotted lines. Fig. 3 is a view in cross-section of the front end of the sewing machine bed-plate and the loop-taker actuating shaft, with the left-hand and rear side loop-takers 35 in elevation. Fig. 4 is a plan view of the needle or throat-plate. Fig. 5 comprises views, in perspective, of one of the complementary loop-takers, complementary bobbin-case oscillating levers, complementary pin-followers, the loop-taker frame located back 40 of the needle, and the bobbin-case lever adjusting plate common to the present loop-takers with the exception that, for use in connection with the present right and left hand loop-takers there must be provided 45 openings as represented by the circular dotted lines, later to be referred to. Fig. 6 is a diagrammatic view illustrating certain changes in the relative arrangement of the loop-seizing points of the loop-takers and 50 coacting needles to meet the requirements of the invention. Figs. 7 and 8 are views illustrating like and unlike leads of seam formation, respectively.
- 55 The invention is herein shown and will be described in connection with so much of one variety of Singer commercial three-needle sewing machine as is deemed sufficient for an understanding of its application, and is intended to comprise improved means over 60 that represented by United States patent application of Corrall and Stevens, Serial No. 868,908, filed October 27, 1914.
- 65 Referring to the figures, 1 represents the sewing machine frame provided with the integrally formed bed-plate 2, 3 the lower end portion of one form of commonly employed needle-carrying bar controlled to effect reciprocatory stitch-forming movements by common means (not shown), 4 the needle-bracket 70 or holder fast on the needle-carrying bar and 5, 6 and 7 needles removably secured in said needle-holder.
- 75 8 represents the loop-taker actuating shaft actuated by common means from one form 75 of commonly employed main or needle-bar actuating shaft (not shown), 9, 10 and 11 gear members carried by said loop-taker actuating shaft, the latter gear member being shown in dotted lines only, said gear members meshing with the respective gear members 12, 13 and 14 fast on the respective loop-taker shafts 15, 16 and 17 provided with the respective loop-takers 18, 19 and 20.
- 80 As the loop-takers and the elements carried and actuated by the latter, now to be referred to, are each a duplicate of the others, except in the providing of certain openings represented by circular dotted lines, Fig. 5, later to be referred to, said 85
- 90
- 95
- 100
- 105
- 110

complemental elements will be referred to singly and designated in the drawings by like numerals.

21 represents the bobbin-case lever adjusting plate fulcrumed upon a hub 22 of the loop-taker frames and held against accidental movement by the screws, as 24, the loop-taker frame 23 being secured to the machine frame by screws, as 25, and the 10 loop-taker frames, as 23' adjustably secured by screws, as 25'. 26 denotes the bobbin-case oscillating lever journaled on an eccentric 27 carried by the loop-taker washer 28 held by pin 29 to rotate with the loop-taker, 15 the plate 21 being provided with an opening 30 into which is loosely seated a pin 31 provided with a follower 32 tracking the forked opening 33 in the oscillating lever 26, which latter is provided with a bobbin-case actuating finger 34. In the sequence of movements of the elements above referred to for effecting an opening for the needle-thread loops, the eccentric 27 acts upon the bobbin-case lever 26 to, through the pin 31 as a 20 pivot, oscillate the finger 34 which causes its free end to be moved into contact with the incline 36 of the web 37 carried by the bobbin-case 38 and oscillate the latter sufficient to place the bobbin-case stop-lug 39 25 central between the oppositely arranged stop-lugs as 40, depending from the throat or needle-plate 41, thus effecting an opening between said stop-finger and its coacting lug 40 for the passage of the thread 30 loop, as in earlier constructions.

To accommodate the adjustments of the loop-takers 18 and 20 so that their loop-seizing points will coöperate with their respective needles 5 and 7, when arranged in 10 line with needle 6, as in Fig. 2, or in any position between said line and the dotted line $a-a$, Fig. 6, their bobbin-case lever adjusting plates 21 are provided with additional openings, as represented by dotted 15 lines 42, so that the pin 31 and follower 32 may be positioned to meet the requirements of changes in their timing. The advantages in providing means for giving like and unlike leads to multiple seams effected at a 20 single operation will now be pointed out in connection with a single product, it being evident that the advantages have like or similar application to products generally.

Figs. 7 and 8 illustrate such portion of a 5 woman's corset as includes a portion of the stay pockets, as 43, for the commonly employed steels or other stays (not shown) and a portion of the elastic web 44 employed to permit of the lower portion of the corset 10 expanding about the hips. In forming the stay pockets it is sometimes desirable that the seam 45 shall finish short of the point at which the outer seams 46 and 47 finish to better facilitate the entering of the end 15 of the stays into the pockets and especially

is this desirable when the pockets are to be closed by flossing or other ornamentation as indicated by 47', the difference in lead being somewhat dependent upon the width of the stay employed, but in the operations 70 of feeding in the stays as the pockets are being stitched, as in the cheaper grades of corsets, it is desirable that the seams have the same lead as shown in Fig. 7. The stitching of a corset has been herein selected 75 for demonstrating the application of the invention as its development was in connection with such operations.

As the present feeding mechanism comprises one form of commonly employed 80 feed-dog 48 and common means for effecting its step-by-step feed movements it is not deemed necessary to refer to such means, but it is desirable to the present invention that the feed-dog be located at the rear of its 85 commonly employed position to better present the fabric to the action of the needles when the latter are arranged in a straight line, as in Fig. 2, and when the feed-dog is so positioned its feeding action extends a 90 substantial distance back of the needles and over the loop-taker 19 and under certain adjustments of amplitude of feed movement the feed-dog overlaps the thread bobbin 49 when in its advanced position, but withdrawn from such overlapping position when in its retracted position or position to commence its feed movement, thus permitting 95 of the convenient replenishing of the bobbin-thread.

The needle-plate 41 is provided with parallel extensions or arms 50 and 51 whose inner walls are provided with guideways, as 52, into which is slidably mounted the back slide-plate 53 provided with notches 100 or slots, as 54, comprising extensions of the feed slots, as 55, to accommodate the feed movements of the feed-dog when of an amplitude to effect a comparatively small number of stitches to the inch, as is common in 110 the stitching of many products, said needle-plate being secured upon the bed-plate 2 by screws, as 56. 57 and 58 denote the front and back slide-plates, respectively.

Having thus set forth the nature of the 115 invention, what I claim herein is:—

1. In a stitch-forming mechanism for sewing machines, the combination with triangularly arranged loop-takers provided with loop-seizing elements and having stitch-forming movements in a given plane, of co-operating needles having stitch-forming movements in paths at substantially right angles to said plane, the loop-seizing elements of the loop-takers coöperating with the outer of said needles seizing the loop of needle-thread on a line crossing its own axis at a substantial angle to a line intersecting the axes of the loop-takers coöperating with the outer of said needles.

2. In a stitch-forming mechanism for sewing machines, the combination with triangularly arranged loop-takers provided with loop-seizing elements having stitch-forming movements in a given plane, of coöperating needles having stitch-forming movements in paths at substantially right angles to said plane, the loop-seizing elements of the loop-takers coöperating with said needles to seize the loops of needle-thread in substantially the same horizontal and vertical planes.
3. In a stitch-forming mechanism for sewing machines, the combination with triangularly arranged loop-takers provided with loop-seizing elements and having stitch-forming movements in a given plane, of coöperating needles arranged in the same vertical plane within the field described by the triangularly arranged axes of said loop-takers and having stitch-forming movements in paths substantially at right angles to said given plane.
4. In a sewing machine, the combination with a stitch-forming and cloth-feeding
- 5 movements in a given plane, of coöperating needles having stitch-forming movements in paths at substantially right angles to said plane, the loop-seizing elements of the loop-takers coöperating with said needles to seize the loops of needle-thread in substantially the same horizontal and vertical planes.
- 10 15 20
- mechanism including triangularly arranged loop-takers and coöperating needles, of means for supporting the fabric being acted on including a slide-plate located back of the line of needle actuation and a needle-plate, the latter forked to receive said slide-plate.
- 25 30
5. In a sewing machine, the combination with a stitch-forming and cloth-feeding mechanism including a feed-dog, triangularly arranged loop-takers and needles coöperating with the latter to form stitches, of means for supporting the fabric being acted on including a needle-plate and a slide-plate provided with feed-dog openings, said needle-plate being forked to receive said slide-plate.
- 35 40

In testimony whereof, I have signed my name to this specification, in the presence of two subscribing witnesses.

JOHN C. RINGE.
